Patented Jan. 3, 1922.

UNITED STATES PATENT OFFICE.

WILLIAM H. MENSCHING, OF BROOKLYN, NEW YORK.

TOOL HOLDER.

1,402,001.

Specification of Letters Patent. Patented Jan. 3, 1922.

Application filed February 17, 1921. Serial No. 445,881.

To all whom it may concern:

Be it known that I, WILLIAM H. MENSCHING, a citizen of the United States, residing at Brooklyn, in the county of Kings 5 and State of New York, have invented certain new and useful Improvements in a Tool Holder, of which the following is a specification.

My invention relates to an improved tool 10 holder adapted to adjustably retain an edged tool therein. The primary object is the provision of a portable tool holder to be used in connection with an abrasive surface, for grinding or sharpening of the tool, and 15 which is adapted to be used as a plane, or grooving tool.

Another object is the provision of a tool 20 holder having novel means for ready and accurate adjustment of the tool held there- 25 by, to any desired angle for sharpening or cutting.

With these and other objects in view, which will be apparent from the description, my invention resides in the novel com- 25 bination, construction, and arrangement of parts hereinafter described and claimed, and illustrated in the accompanying drawings, of which;

Fig. 1, is a plan view of the holder, 30 Fig. 2, a side elevation, showing a tool in position,

Fig. 3, a section on line 3—3 of Fig. 2,
Fig. 4, a detail of a part employed.

Throughout the description and the sev- 35 eral views, like reference numerals designate like parts. In the preferred form the holder comprises a substantially rectangular frame formed of two similar openwork castings 1 and 2, provided at their ends with 40 ears 3 and fastened together by suitable se- curing means 4 positioned in the ears. The sides of the frame comprise upper bars 5 and lower bars 6, with diagonal webs 7 ex- tending therebetween. These webs are pro- 45 vided with arcuate slots 8, for a purpose to be hereinafter described. Correspond- 50 ingly slotted side plates 9 are suitably se- cured over the sides of the frame for greater structural strength, as well as convenience in handling the device.

Disposed between the sides of the frame and substantially intermediate the ends, is the tool clamping and adjusting member, comprising a base plate 10, pivoted at its 55 lower end to the bottom bars 6 of the frame

by means of pins 11 journalled in the lower bars and disposed in lugs 12 formed on the plate. An integral, substantially U-shaped frame extends from the sides of the plate 10 laterally thereof, to form side walls 13 and an outer bar 14, spaced from the plate 60 and parallel therewith. The walls 13 are reduced toward bar 14, whereby the bar is aligned with the central portion of the base plate 10. 65

Bar 14 is provided with a central thick- ened portion 15 internally threaded to re- ceive a winged bolt 16 carrying a clamping plate 17 on its inner end, whereby a tool 18 may be clamped in the holder between base 70 plate 10 and the clamping plate 17. The angular adjustment of the tool is obtained by means of set screws 19 disposed through the slots 8 and threaded into integral lugs 20 on the rear face of the base plate 10. The 75 heads of the set screws 19 are preferably winged, to bear against the side plates 9 for frictional engagement. Adjacent the webs 7, and also the opposite end portion of the frame, steel rollers 21 are journalled 80 between the lower frame bars 6; the periph- eries of the rollers extending beneath the frame. For the purpose of insuring rigidity to a tool carried in the holder, I provide keys 22 having channelled heads 23 adapted 85 to be engaged over the upper edge of the base plate 10 between the side walls 13 and the tool. These keys are intended for use with small size bladed tools such as chisels and the like and may vary in size to meet 90 the individual requirements.

The device is adapted to be rolled over a plane abrasive surface, such as emery and the like, and the rollers will serve to dis- tribute oil in an efficient manner. 95

In operation, a desired tool is inserted in the holder and clamped between base plate 10 and plate 17 with the edge of the tool 100 projecting below the frame the distance de- sired. The angle of the edge is then adjusted by moving the clamping member on the pivots 11 and locking it in position by means of the set screws 19. It is obvious that with the proper blades, the device may be used as a plane, or grooving tool, the operation be- 105 ing the same.

While I have shown and described certain details which enter into the construction and operation of my invention, I desire it to be understood that I do not limit myself to 110

these, but may use any such as will fall within the scope of the invention as claimed.

I claim:

1. A device of the character described comprising a substantially rectangular frame having side and end walls, a plate disposed in the frame between the side walls and pivoted thereto, a clamp support carried by said plate, a clamp in said support for 10 clamping a tool against said plate, means carried by said plate for slidably engagement with the side walls of said frame for angular adjustment of said plate relative to the frame, and supporting rollers in the 15 frame adjacent the end walls thereof.
2. A device of the character described comprising a frame formed of two similar openwork castings, webs in the castings and provided with arcuate slots, a tool clamping member pivoted in the frame, and means for 20 angular adjustment of said clamping member, carried thereby and disposed in said slots.
3. In a tool holder, a portable frame, 25 rollers arranged therein for supporting said frame, a plate pivoted in the frame, a clamp

carried by said plate, an edged tool retained in said clamp and extended beneath said frame, and means carried by said plate adapted to slidably and adjustably engage 30 the sides of the frame for angular adjustment of the plate.

4. A tool holder comprising a frame having side and end walls, supporting rollers arranged between the side walls, a clamping member adapted to receive an edged tool disposed in the frame and comprising a base plate pivoted at one end to the side walls of said frame, an integral U shaped member extending laterally of the base 40 plate between the side walls of the frame, a bolt threaded in said U shaped member, a clamping plate carried by said bolt, the side walls of said frame being slotted, lugs on said base plate, and set screws disposed in 45 said lugs and positioned in said slots for clamping engagement with the side walls of the frame for angular adjustment of the clamping member in the frame.

In testimony whereof I affix my signature. 50

WILLIAM H. MENSCHING.
